TEXTILE TUBING MACHINE

Paul Thourot, Passaic, N. J., assignor to Martin
Weiner, Passaic, N. J.

Application April 26, 1939, Serial No. 270,078

10 Claims. (Cl. 242—57)

The present machine relates to the handling and separation of textile pieces sewed together and brought to the machine on reels. The pieces are generally from 50 to 70 yards and the total length of the multiple pieces seamed together is generally from 300 to 400 yards. The function of the machine is to wind the textile in suitable lengths on a paper tube ready for delivery to a customer and a specific length may be that of a single piece or a plurality of pieces. The winding operation is effected at high speed and the object of the present improvement is to provide means for stopping the machine to bring the seam joining separate pieces into a predetermined convenient position for cutting the seam and making ready a succeeding piece for winding, without imposing shock and undue strains upon the high-speed rotating members or the textile piece, notwithstanding the fact that the rotational elements of the machine are under a high degree of momentum when the stopping devices are applied. Further objects will hereinafter appear.

The invention will be described with reference to the accompanying drawings, in which:

Figure 1 is a front elevation of an embodiment of the invention.

Figure 2 is an end elevation, taken from the motor end.

Figure 3 is an enlarged elevation, partly in longitudinal section, showing the automatic seam-operated switch mechanism.

Figure 4 is a plan view of the structure shown in Figure 3.

Figure 5 is a vertical section on the line 5—5, Figure 3.

Figure 6 is a schematic wiring plan.

Referring to the drawings, I have shown at 1, 1x, opposed heavy vertical frame members connected by the tie-rods 2. Each frame member carries an inwardly projecting axle 3 upon which is mounted one of the two opposed swing-brackets 4, each bracket being provided with three bearing members so that upper bearing members 4x are provided for the shaft 5 of a drum 6, intermediate bearing members 4xx are provided for the shaft 7 of a guide roller 8, and lowermost bearing members 4xxx are provided for the shaft 9 which carries the guide roller 10.

The supply drum 11, Figure 2, is rotationally carried by any suitable means supported by bracket such as 12 and the fabric is lead from the supply drum (as shown by the dotted lines t, Figure 2) over roller 10 under guide roller 8, thence partially around drum 6, the textile being held down upon the drum by a pressure roller 13 car-

ried by suitable arms such as 14 pivoted at 15. The textile then extends to and over a guide roller 16 on a shaft 17 and directly to the paper tube indicated by dotted lines p, Figure 1, the tube being held by pintles 18 having sleeves 18x on stud shafts 19. While the pintles 18 are retractable with the sleeves which carry them, these sleeves will be suitably keyed to shafts 19 so that rotation of the shafts will impart rotation to the tube p.

The textile is pulled from the supply drum by 10 rotation of the paper tube through positive rotation of stud shafts 19. For such purpose the end of each stud shaft is given firm bearing support within a housing 20 carried by the frame member 1 or frame member 1x, as the case may be, and each shaft 19 carries a sprocket wheel (not shown) over which is led a chain, one of the chains being indicated in Figure 2 at 21. Each chain is led over an idler sprocket wheel such as 22, Figure 2, and thence over a drive sprocket 20 such as indicated at 23, Figure 2, the drive sprocket being on a shaft 24, one end of the shaft projecting outwardly from the frame member 1x and carrying a pulley 25 adapted to be clutched to shaft 24 by the endwise movable clutch member 26. The pulley 25 is driven by a belt 27 from a drive pulley 28 on the shaft of a motor 29.

A clutch operating lever 30 is pivoted at 31 on a suitable bracket carried by the frame member 1x and is normally held against a stop pin 32, Figure 2. To the clutch operating lever is secured a link 33 connected to the lower end of a rock arm 34 pivoted at 35 (Figure 1) on a bracket plate 36. The pivot member for rock arm 34 is a shaft to which the rock arm is secured, and carried by 35 the shaft is a foot-operating lever 37 having two foot pedals, i. e., pedals 37x and 37xx. When pedal 37xx is depressed, rod 33 will be moved to the left from its position shown in Figure 1 and the clutch will be operated to rotate drive shaft 40 24. As pedal 37xx is depressed, a latch hook 38 will snap over a latch finger 39 and thus the clutch will be held in operative position. Latch hook 38 is pivoted at 38x and normally held in the position of Figure 1 by a spring 40.

The relation of latch hook 38 and latch finger 39 is such that depression of pedal 37xx will cause disengagement of the latch hook from the finger; also positive movement of the latch hook to the right from its position in Figure 1 will effect release of the latch finger. In the cycle of operation, such a releasing movement of the latch hook is effected by a solenoid, the solenoid winding being disposed in box 41 and the core 42 being pivoted to the latch hook at 43.

By reference to Figure 2, it will be seen that the supply drum for the seamed textile pieces carries a small brake drum 11x disposed between two brake levers 44 normally engaging the brake drum 11 through the action of a spring 44x but held out of braking relation with the drum through the action of a solenoid 45. When a circuit through the solenoid, later to be described, is broken the brake is released and comes into action. Any suitable operating connections between solenoid 45 and the brake levers 44 may be employed and hence I have not shown such connection in detail.

By reference to Figures 1 and 2 it will be seen that one of the two positively driven shafts 19, i. e., that affording a bearing support upon frame member 1x, carries a pulley 46 which drives a belt 47 which rotates a pulley 48 carried by a governor shaft 49. On the shaft is mounted a usual type of ball governor 50 which, when the machine is at rest, depresses the rear end of switch lever 51, carrying its contact point out of engagement with the contact point of a switch finger 52. Switch lever 51 receives current via wire a and switch finger 52 receives current via wire b. As the fabric passes from guide-roller 10 to drum 6, it passes over a smooth-surfaced disk 53 best shown in Figures 3 and 5. This disk is held on the upper end of a vertically movable rod 54 and is carried by a bearing member 55 within a switch box 56, the lower insulated end of the rod engaging a spring switch arm 57 having a contact on its lower face and in register with a similarly formed switch finger 58. Above the textile sheet and in contact therewith, is a second smooth-faced disk 59 carried by a threaded shaft 60 which is threaded in an aperture formed in a bracket arm 61. On the upper end of threaded shaft 60 is a dial-surfaced thumb piece 60x, and a pointer 62 is carried by bracket arm 61.

It is intended that the thickened line caused by the seam joining two textile pieces will close the switch comprising members 57 and 58 and therefore contact disk 59 is held in adjusted, but fixed, position, and disk 53 with its rod 54 will be moved downwardly a distance equivalent to the thickness of the seam. If the thickness of the seam is insufficient to bring the switch contacts together, rotation of thumb disk 60x may be had to move switch arm 57 closer to its co-acting member 58 and the dial and pointer will at all times indicate the distance between the switch contacts.

55 A brake is provided for drum 6. To this end the drum shaft 5 carries a brake pulley 62 over which passes a brake band 63, one end of the band being held by a yoke 64 supported from frame member 1x and the opposite end of the band being connected at 65 to the core of a solenoid or brake magnet BM.

In the operation of the machine, the textile is led from the supply reel over guide roller 10 and thence between the disks 53 and 59 of the feeler switch mechanism, thence around the surface of drum 6 to guide roller 16 and thence to the paper tube p. Pedal 37x is then depressed until finger 39 is engaged by latch hook 38, and rod 33 will be moved to the left from its position in Figure 1, causing the clutch to engage, thus rotating shaft 24 and, through drive chains 21 effecting rotation of stud shafts 19 and the paper tube p. When a seam meets disk 53, rod 54 will be depressed and the feeler switch comprising members 57 and 58 will close a circuit

through the clutch magnet or solenoid 41, pulling latch hook 38 clear of the finger 39, whereupon rod 33 will move to the position of Figure 1 under the influence of the clutch-releasing spring (not shown) and the power rotation of shaft 24 will be stopped. As the clutch is released, rock arm 34 will be moved to the position of Figure 1 and through its connection with a link 66, which is, in turn, connected to a lever arm 67, a mercury switch A will be moved to the position of Figures 1 and 6, closing a circuit leading through the brake magnet BM, thus operating the band brake member 63 to stop the momentum of drum 6. The said circuit comprises a positive wire d, branch wires e, e', the brake magnet BM, return wire f, mercury switch A, governor switch wire b, the governor switch and return wire a. Inasmuch as declutching shaft 24 from the power drive will not, of itself, stop rotation of the machine elements, this continued rotation will keep open the governor switch until the circuit is completed through the brake member for the drum. When the machine is brought to a stop the governor also stops and the descent of the governor weights operates pivoted switch arm 51, opening the circuit through wires a and b. At this point the seam has passed the feeler switch and its contacts are open, thus the clutch solenoid or magnet will be de-energized. The opening of the governor switch also will de-energize the brake solenoid for the drum 6.

The spring brake for the supply reel, which is held to released position by solenoid 45 and its connections when the machine is running, is controlled as follows:

A tilting mercury switch C (Figure 6) will be suitably mounted upon the pedal shaft 35 in such manner that slight depression of pedal 37xx will close the contacts thereof prior to any such extent of movement of link 33 as would engage the clutch latching member 38, 39. Also when pedal 37 is fully depressed, throwing the machine into motion, the contacts of mercury switch C will remain closed, to be opened only by the full release of pedal 37xx to the position shown in Figure 1. By reason of such construction, slight depression of pedal 37x will close a circuit through the positive wires d, e, to electric brake solenoid 45, the return wire being h, thence through the mercury switch C to return wires k. Thus the supply reel will be released by the releasing action of the electric brake solenoid 45, enabling the operator, after cutting out a seam, to pull enough slack to start winding on a new tube.

By reason of the above combination of elements, the seam feeler circuit is closed only for an instant, when releasing the clutch, whereupon the drum brake circuit and the supply reel brake circuit are closed and opened respectively, throwing into operation a brake for the drum and a brake for the supply reel, and finally, when the machine stops no current flows through any circuit. By reason of the controlled stopping of the machine, the momentum of rotating elements, the major element of momentum being the drum 6, is so controlled as to relieve the machine and the textile itself of undue strain and to carry the seam to a point where it is stopped most conveniently for the operator as, for example, midway of the area between guide roller 16 and the shafts 19. Any adjustment in timing desired, with respect to the degree of movement of the seam from the feeler switch may be effected by movement of a threaded stem 68 carrying yoke 64. The stem passes through an aperture in

bracket arm 69 and may be held in adjusted position by nut 70. By such adjustment the braking action of the drum bracket magnet BM may be slightly increased or decreased to change the 5 length of movement of the seam away from the feeler switch.

It will be seen that the machine may be stopped independently of the seam feeler switch by depression of pedal 37xx. It will also be understood 10 that various modifications may be made in the form and arrangement of the elements constituting the embodiment illustrated in the drawings without departing from the spirit of the invention.

15 Having described my invention, what I claim and desire to secure by Letters Patent is as follows:

1. In textile tubing machines comprising a frame, means for rotatably supporting a supply 20 reel for a plurality of textile pieces seamed together, a shaft for rotating a tube for winding-in the textile, an intermediate guide drum; a drive shaft and drive connections for the tube-rotating shaft, power drive means and a clutch 25 between said means and the drive shaft, electrically operable declutching means, a seam-operable switch, a circuit including said switch and declutching means, an electrically operated brake for said guide drum, and a circuit therefor including a switch closed by movement of said declutching means, to energize said brake and throw it into operative action to stop said drum, and an inertia switch normally closed by rotation of the tube-rotating shaft and adapted to open said last 35 named circuit upon the stoppage of rotation of said tube-rotating shaft.

2. In textile tubing machines comprising a frame, means for rotatably supporting a supply reel for a plurality of textile pieces seamed together, a shaft for rotating a tube for winding-in the textile, intermediate rotary guiding and control means for the textile, power drive means for the tube rotating shaft including a power device and electrically operated disconnecting means 40 therefor, an electric circuit for said disconnecting means, a seam-operable switch in said circuit, an electrically operated brake for stopping said guiding and control means, an electric circuit for said brake including a switch operated by said disconnecting means, and an inertia switch in 45 said brake circuit, said last named switch being normally closed by rotation of the tube rotating shaft and adapted to open its circuit upon stoppage of rotation of said tube rotating shaft.

55 3. A textile tubing machine constructed in accordance with claim 2, in combination with a spring brake for the supply reel, electrically operated releasing means for said brake, an electric circuit for said releasing means, and a switch adapted to open said circuit and connected to the clutch disconnecting means for operation simultaneously therewith.

4. A textile tubing machine constructed in accordance with claim 2, in which the electrically 60 operated disconnecting means for the power drive comprises a clutch for the power device, a pedal operated clutch engaging device and spring releasing means therefor, a latch for said clutch engaging device, and an electrical latch-releasing device in the seam-operable switch circuit.

5. A textile tubing machine constructed in accordance with claim 2, in which the inertia switch comprises normally closed contact members, a centrifugal device gravitationally opening said members when the machine comes to rest, and a drive connection between a rotary member of the machine and said centrifugal device. 5

6. A textile tubing machine constructed in accordance with claim 2, in combination with an electrically releasable supply reel brake, a circuit therefor, and a switch member for said circuit in which the switch members for said supply reel brake releasing circuit and the circuit for the rotary guiding and control means for the textile are tilting mercury switch members connected to, for simultaneously operation by, the power disconnecting means, the first moving into circuit opening position and the second into circuit closing position. 10

15 7. A textile tubing machine constructed in accordance with claim 2, in combination with an electrically releasable supply reel brake, a circuit therefor, and a switch member for said circuit in which the switch members for said supply reel brake releasing circuit and the circuit for the rotary guiding and control means for the textile are tilting mercury switch members connected to, for simultaneous operation by, the power disconnecting means, the first moving into circuit opening position and the second into circuit closing position, in combination with a pedal device adapted to move the mercury switch for the supply reel brake releasing circuit into circuit closing position whilst the switch for the rotary guiding and control means circuit remains in circuit closing position and the power remains disconnected. 20

25 8. A textile tubing machine constructed in accordance with claim 2, in which the seam-operable switch comprises normally spaced contacts, an endwise movable closure member for said contacts having a head for engagement by one face of the textile, and an adjustable engaging abutment for the opposite face of the textile. 30

35 9. A textile tubing machine constructed in accordance with claim 2, in which the seam-operable switch comprises normally spaced contacts, an endwise movable closure member for said contacts having a head for engagement by one face of the textile, a normally fixed abutting member 40 for the opposite face of said textile, and means for adjusting said abutting member toward and from the endwise movable contact member to change the operative position of the latter. 45

50 10. A textile tubing machine constructed in accordance with claim 2, in which the seam-operable switch comprises normally spaced contacts, an endwise movable closure member for said contacts having a head for engagement by one face of the textile, a normally fixed abutting member 55 for the opposite face of said textile, means for adjusting said abutting member toward and from the endwise movable contact member to change the operative position of the latter, and a dial device connected with said adjusting means 60 for indicating the distance between the contacts preliminary to a switch closing actuation by the seam. 65
